UNITED STATES PATENT OFFICE.

LEWIS J. MULLER, OF PHILADELPHIA, PENNSYLVANIA, ASSIGNOR OF ONE-HALF TO
ALBERT L. ROWLAND, OF OAK LANE, PENNSYLVANIA.

TABLE.

Application filed December 9, 1926. Serial No. 163,522.

This invention relates to improvements in tables used in cafeterias, lunch-rooms, restaurants, clubs, and similar places.

The object of the invention is to provide a table and seats which are mounted upon a single pedestal, and to so arrange them that the seats can be turned on their pivots so as to be located wholly under the table-top when not in use, and which will facilitate the cleaning of the floor under the seats and tables, by eliminating the usual necessity of placing the chairs on the table-tops with consequent damage to the tops during such cleaning, and also reduce the labor involved in such cleaning.

The invention also provides seat sections which are detachable from the base, so that, in the event of breakage, one seat section can be readily detached and replaced by another section.

In the accompanying drawings:

Figure 1 is a plan view of the improved cafeteria table;

Figure 2 is a side view, showing one of the seats in section;

Figure 3 is a plan view, showing the seats turned under the table-top, the table-top being shown by dotted lines;

Figure 4 is a vertical sectional view of the pedestal;

Figure 5 is a detached side view of a seat bracket;

Figure 6 is a plan view of a seat bracket;

Figure 7 is a view showing a part of the base in section, and the pivot for a seat section in full lines;

Figure 8 is a sectional plan view on the line 8-8, Figure 7 and

Figure 9 is a sectional view illustrating the method of securing the table-top to the pedestal.

The pedestal 1 has an extended base 2, and an enlarged upper portion 3 as shown in Figure 4. The pedestal is of metal and is made hollow. The upper portion 3 has four arms, in the present instance, which are perforated for the passage of the bolts 4 which secure the table-top 5 to the pedestal, as shown in Figure 9.

The table-top 5 is circular in the present in-

stance, but it will be understood that it may be made in other shapes without departing from the essential features of the invention.

The base 2 of the pedestal has four extensions, in which are sockets 6 for the pivots 7 of the seat arms 8, which latter are curved as shown in Figures 5 and 6 so as to extend beyond the base when in use.

At the lower end of each arm is a flange 9 which rests upon the base as shown in Figure 7, and depending from each flange is a lug 10 which is located in an extended notch 11 in the base, the end walls of this notch limiting the outward and inward movement of the arm, and also preventing the arm being moved in the wrong direction. By this arrangement, the seat 12, carried by the arm, is in the proper position when extended, and when turned under the table-top, as in Figure 3, its movement is limited so that the seats will not strike each other nor the pedestal.

In order to hold the seat arms in the sockets 6, set-screws 13 are provided, which are tapped into the extensions of the base and project into segmental slots 14 in the pivots 7 of the arms 8, as clearly shown in Figures 7 and 8. On withdrawing the set-screws, the seat sections can be readily removed from the base for repairs or replacements.

Each seat arm 8 is enlarged at the upper end 15 to form a firm support for the seat 12 to which it is secured.

The seats may be in the form of stools without backs, or they may be made as shown in Figure 2 with backs 16. These backs are of such height that they will pass under the table-top 5 when the seats are moved under the table, as in Figure 3.

In equipping a cafeteria or similar place with the table above described, a minimum amount of space is occupied by the table, so that a great number of tables can be located in a comparatively small space. When the floor is to be mopped, all that is necessary is to turn the seats under the table, the seats remaining in such position until occupied, when they can be readily withdrawn. This arrangement provides a clear aisle space when the seats are not occupied.

While the table is shown with four seat

sections, the number of seats may be varied, depending somewhat on the diameter of the table.

The seats are so designed that the arms do not interfere with access from either side of a seat, and there is no straddling of the arms by the occupant.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claim.

Having thus described my invention, what I claim as new and desire to secure by Letters Patent is:

20 The combination of a table pedestal, means for attaching a top to the upper part of the

pedestal, extensions at the foot of and integral with the pedestal, said extensions being substantially perpendicular to the table supporting portion, with their under sides in the same 25 plane as the bottom of the table supporting portion, each extension having a socket therein, the axis of the socket being parallel to the axis of the table supporting portion, a seat supporting arm for each socket, the bottom of 30 each arm having a pivot with a flange thereon, the pivot being adapted to fit within, with the flange resting on, the socket, a lug depending from each flange, a notch in each said extension adjacent the socket and adapted to 35 receive the lug and limit the movement of the lug in the extension, and means for preventing the accidental removal of the pivot from the socket.

In testimony whereof I have signed my 40 name to this specification.

LEWIS J. MULLER.
